UNITED STATES PATENT OFFICE.

GEORGE HYLER AND GLENN FISHER, OF LANSING, MICHIGAN.

AUTOMATIC RAILWAY-GATE.

1,050,465.

Specification of Letters Patent. Patented Jan. 14, 1913.

Application filed October 21, 1911. Serial No. 655,856.

To all whom it may concern:

Be it known that we, GEORGE HYLER and GLENN FISHER, citizens of the United States, residing at Lansing, in the county of Ingham and State of Michigan, have invented 5 certain new and useful Improvements in Automatic Railway-Gates, of which the following is a specification.

The present invention relates to certain 10 new and useful improvements in the construction of railway gates of that general character which are automatically lowered at the approach of a train to a crossing, and automatically raised after the train 15 has passed the crossing.

The object of the invention is to provide 20 an automatic railway gate which is comparatively simple and inexpensive in its construction, which is positive and reliable in its operation, which will not be constantly getting out of repair, and in which the various elements can be properly housed so as to be shielded from rain and snow.

With these and other objects in view, the 25 invention consists in certain novel combinations and arrangements of the parts as will more fully appear as the description proceeds, the novel features thereof being pointed out in the appended claims.

For a full understanding of the invention, reference is to be had to the following 30 description and accompanying drawings, in which:

Figure 1 is a transverse sectional view 35 through a railway track having the automatic gates mounted upon opposite sides thereof. Fig. 2 is a plan view of a crossing provided with the automatic gates, the parts being shown diagrammatically and 40 the gates appearing in a lowered position. Fig. 3 is a plan view in which the various electric circuits are diagrammatically shown, the various switches being in the position assumed at that instant when the 45 train has passed the crossing and the gates are to be raised. Fig. 4 is a detail sectional view through one of the main casings and showing the gearing for raising and lowering the gates. Fig. 5 is a detail sectional 50 view through one of the trip actuated switches which serve to actuate the mechanism for lowering the gates when a train approaches the crossing from either direction. Fig. 6 is a similar view taken at right 55 angles to Fig. 5. Fig. 7 is a detail sectional view of the trip actuated switch which is

utilized for setting the mechanism in motion for raising the gates after the train has passed the crossing. Fig. 8 is a detail view of the switch which is actuated by 60 the gates to stop the motor when the gates have been either raised or lowered, and Fig. 9 is a diagrammatic view of the switch controlling one of the motor circuits.

Corresponding and like parts are referred to in the following description and indicated in all the views of the drawings 65 by the same reference characters.

Referring to the drawings, the letter A designates a railway track, and B a road or 70 highway which crosses the track. Gates C are arranged upon opposite sides of the railway track A, and mechanism is provided whereby these gates are automatically lowered as a train approaches the 75 crossing, and automatically raised as the train leaves the crossing. A suitable bell would be provided, and means would be provided for sounding this bell for a sufficient time prior to lowering the gates, so 80 that there would be no danger of a vehicle or pedestrian being trapped between the lowered gates.

We will first describe the specific manner of mounting the gates and the gearing 85 for raising and lowering the same.

Each of the gates comprises a casing 1 which is preferably closed so as to exclude rain and snow, the said casing being mounted upon a base 2 of concrete or other suitable 90 material. A transverse shaft 3 is journaled within the upper portion of the casing 1 and the ends of this shaft project beyond the casing and have the usual gate irons 4 applied thereto. One end of each of the 95 gate irons is weighted as at 5, while the opposite end thereof has the gate bar 6 applied thereto. The shafts 3 of the two gates on opposite sides of the crossing are each suitably connected as by means of a chain 100 and sprocket 7 to a transverse shaft 8 which extends under the track A and is suitably housed within a tubular casing 9. The ends of this casing 9 are provided with suitable bearing members 10 within which 105 the shaft is journaled. One end of the shaft 8 is connected by the gearing 11 to a motor 12 which serves to lower the gates, the said motor being mounted within the adjacent casing 1. The opposite end of the shaft 8 110 is connected by similar gearing 13 to a similar motor 14 which serves to raise the gates,

the said motor being mounted in the adjacent casing 1.

A trip actuated switch D is mounted upon the track at a suitable distance on each side of the crossing. Each of these switches comprises a casing 15 which is closed at the top so as to exclude rain and snow, a horizontal shaft 16 being mounted within the casing and one end of the said shaft projecting through the end of the casing and being provided with an upwardly extending trip arm 17. At a point within the casing the rock shaft 16 is provided with a switch blade 18 adapted to engage the contacts 19 so as to bridge the same and close a circuit 20. A finger 21 projects downwardly from the rock shaft 16 within the casing and is connected by the springs 22 to opposite sides of the casing. These springs normally hold the 25 rock shaft yieldingly in such a position that the switch blade is out of contact with the members 19 and the trip arm 17 projects upwardly. However, when the trip arm 17 is engaged by a wheel flange or a suitable 30 member upon the train, the rock shaft will be moved so as to bring the switch blade 18 into temporary contact with the members 19 and momentarily close the circuit 20. One of these circuits 20 is provided for each of 35 the switches D and a suitable source of current such as the batteries 23 is introduced into each of the circuits. Both of the circuits lead to an electromagnet 24 forming part of a switch E which is utilized for 40 opening and closing the circuit of the motor 12. When either of the switches D is actuated by an approaching train, the magnet 24 is energized so as to attract an armature 25, the said armature being connected to one 45 end of a lever 26 which is pivoted at a point between its ends, as at 27. The opposite end of this lever 26 is connected by a bar 28 to a similar lever 29 which is pivoted at a point between its ends as indicated at 30. 50 The opposite end of the lever 29 carries an armature 31 adapted to be attracted by the electromagnet 32. The connecting bar 28 engages a switch knife 33 which is adapted to bridge the two contacts 34 in order to 55 close the motor circuit 35 and start the motor 12. Any suitable source of power such as that indicated at 36 may be utilized for driving the motor. As soon as the magnet 24 is energized by the approach of a train 60 upon either side of the crossing, the armature 25 is attracted and the levers 27 and 29 moved about their pivots in such a manner as to cause the switch blade 33 to engage the contacts 34 and close the motor circuit. 65 The motor 12 is thereby set in motion so as to lower the gates. As soon as the gates are lowered, a switch F automatically closes a circuit 37 which includes the electromagnet 32. When this electromagnet is energized 70 the armature 31 is attracted so as to move

the levers 27 and 28 and actuate the switch E so as to break the motor circuit 35 and stop the motor. The switch F comprises a contact 38 which is suitably mounted within the casing 1 so as to be engaged by an arm 75 39 mounted upon the shaft 3. The contact members 38 and 39 are interposed in the circuit 37 of the electromagnet 32, the arm 39 projecting laterally from the shaft 3 and being so arranged that the free end thereof is swung into engagement with the contact 38 when the gates have been completely lowered.

A double acting switch G is arranged at the crossing and comprises a housing 40 similar to the housings 15 of the switches D. A horizontal rock shaft 41 is mounted within the casing 40, one end of the rock shaft projecting beyond the side of the casing and being provided with an upwardly extending trip arm 42 adapted to be engaged by a suitable member at the rear of the train. The rock shaft 41 carries a switch blade 43 which when swung in one direction will bridge the contact members 44, and when swung in the opposite direction will bridge the contact members 45. A finger 46 projects from the shaft 41 and is connected by the springs 47 to the sides of the casing so as to normally hold the switch blade 43 in an intermediate and inoperative position, as indicated in Fig. 7. A train moving in either direction will actuate the switch member so as to bridge either the contacts 44 or the contacts 45, both sets of contacts being suitably connected to a circuit 48 including an electromagnet 49. This electromagnet 49 forms part of a switch H which is identical in construction with the switch E and need not be described in detail. As soon as the switch G is actuated, the circuit 48 is closed and the magnet 49 energized. The switch H is then actuated and closes the motor circuit 50 which includes the motor 14, the said motor being thus driven to raise the gates. As soon as the gates are raised a switch I which is identical in construction with the before described switch F is closed, thereby closing a circuit 51 and energizing the magnet 52 of the switch H. The switch H is thereby 110 opened so as to shut off the motor 14. The gates are thus automatically raised after the train has left the crossing, and the parts are all properly arranged so that the gates will be again automatically lowered by a 120 train approaching the crossing from either direction.

Having thus described the invention, what we claim as new and desire to secure by Letters Patent, is:—

1. The combination of a gate, an electro-motor geared to the gate, a motor circuit, a switch controlling the motor circuit and formed with a movable element, a pair of electromagnets, an armature for each of the

electromagnets, an operative connection between the two armatures and the movable switch element, a circuit including one of the electromagnets, means constructed for actuation by moving a train for closing the circuit to energize the magnet, the said magnet operating to move its armature and thereby shifting the movable switch element to close the motor switch, an electric circuit including the opposite electromagnet, and means for automatically closing the circuit when the gate reaches the limit of its movement, the said opposite magnet being then energized and operating to move its armature and shift the movable switch element to open the motor switch.

2. The combination of a gate, an electric motor geared to the gate, a motor circuit, a switch controlling the motor circuit and formed with a movable element, a pair of electromagnets, a pair of levers, armatures mounted upon the levers and arranged in coöperative relation to the respective electromagnets, an operative connection between the levers and the movable switch element, a circuit including one of the electromagnets, means constructed for actuation by a moving train for closing the circuit to energize the magnet, the said magnet operating to move its armature and swing the levers so as to shift the movable switch element and close the motor switch, an electric circuit including the opposite electromagnet, and means for automatically closing the circuit when the gate reaches the limit of its

movement, the said opposite magnet being then energized and operating to move its armature and swing the levers to shift the movable switch element and open the motor switch.

40

3. The combination of a gate, a motor geared to the gate, a motor circuit, a switch controlling the motor circuit and formed with a movable element, a pair of electromagnets, a pair of levers, armatures mounted upon the levers and arranged in coöperative relation to the respective electromagnets, a bar connecting the levers and having an operative connection with the movable switch member, a circuit including one of the electromagnets, means constructed for actuation by a moving train for closing the circuit to energize the magnet, the said magnet operating to swing the levers so as to move the movable switch element and close the motor switch, an electric circuit including the opposite electromagnet, means for automatically closing the circuit when the gate reaches the limit of its movement, the said opposite magnet being then energized and operating to swing the levers to move the movable switch and open the motor switch.
